UNITED STATES PATENT OFFICE.

WILLIAM B. FRUE, OF HOUGHTON, MICHIGAN.

IMPROVED SHAKING-TABLE.

Specification forming part of Letters Patent No. **58,806**, dated October 16, 1866.

To all whom it may concern:

Be it known that I, W. B. FRUE, of Houghton, in the county of Houghton and State of Michigan, have invented a new and Improved Shaking-Table; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention. Fig. 2 is a sectional plan or top view thereof.

Similar letters of reference indicate like parts.

This invention relates to a shaking-table, the top of which is made undulating, or so that it forms a series of concave troughs, in which the ore lodges, and which are provided with projecting points or teeth, and with discharge-channels, in such a manner that by the motion imparted to the table and by the action of the projecting teeth the ore is thoroughly agitated, and the heavy parts are made to pass through the discharge-channels, while the waste is thrown off over the lowest end of each of the concave troughs. The motion imparted to the top of this shaking-table is triple, and thereby the separation of the ore is materially facilitated.

A represents a frame, made of wood or any other suitable material. This frame forms the bearings for the driving-shaft B, on which is mounted a pulley, C, and from this pulley a belt, D, extends to a pulley, E, on the shaft F, as clearly shown in the drawings.

G is the top of my shaking-table, which is suspended by links *a* at one end from pivots *b*, secured in the frame A, and by links *c* at the other end from two cranks, *d*, in the shaft F. The driving-shaft B is also provided with a crank, *e*, which connects by a pitman, *f*, with the top G. By these means a triple motion is imparted to the top—viz., a reciprocating motion by the crank *e* in the driving-shaft, a ris-

ing-and-falling motion by the links *a*, and an oscillating motion by the action of the cranks *d* in the shaft F.

The surface of the top G is undulating, so that the same forms a series of concave troughs, *g*, and said top is hung in an inclined position, somewhat higher at one end than at the other. Each of the concave troughs is provided with a series of teeth, *h*, and with several discharge-openings *i*.

The ore is let on the table at its highest end, and by the motion given to the table the ore is separated according to the specific gravity of the several parts contained therein. The light parts pass off to the next succeeding trough, and the heavy parts discharge through the openings *i*. The teeth *h* serve to agitate the ore as the same passes over the surface of the table, and thereby the separation is materially facilitated. The waste discharges over the lowest end of the table.

If desired, a second table may be placed underneath the first, so that those particles which discharge from the first table undergo a second separation, and thereby all the metal contained in the ore is saved.

What I claim as new, and desire to secure by Letters Patent, is—

1. The undulating top G, forming a series of concave troughs, substantially as and for the purpose described.

2. The agitators *h* and discharge-openings *i* in the several troughs of the top G, substantially as and for the purpose set forth.

3. The crank-shafts B and F and links *a c*, in combination with the table G, constructed and operating substantially as and for the purpose described.

The above specification of my invention signed by me this 7th day of August, 1866.

WM. B. FRUE.
